UNITED STATES PATENT OFFICE.

MAME CECILLIA REESE, OF OXFORD, PENNSYLVANIA.

DESIGN FOR A ROSETTE.

SPECIFICATION forming part of Design No. 22,754, dated August 29, 1893.

Application filed March 17, 1893. Serial No. 466,536. Term of patent 3½ years.

To all whom it may concern:

Be it known that I, MAME CECILLIA REESE, a citizen of the United States, residing at Oxford, in the county of Chester and State of Pennsylvania, have invented certain new and useful Improvements in a Design for a Rosette; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 The leading feature of this design consists in a rosette having a scalloped outline with eight sides and with a corresponding number of depressions, alike upon opposite sides, and each having substantially the shape of an oyster shell.

20

Figure 1 is a view of one side of the rosette, and Fig. 2 is a view of the reverse side.

In the drawings, the letter B designates the rosette which has a scalloped outline with eight sides and a corresponding number of depressions, alike upon opposite sides, and each having substantially the shape of an oyster shell.

What I claim is—

The design for a rosette, substantially as 30 herein shown and described.

In testimony whereof I affix my signature in presence of two witnesses.

MAME CECILLIA REESE.
